CLAIM

The ornamental design for a glove caddy, as shown and described.

DESCRIPTION

FIG. 1 is a front elevation of the glove caddy showing my new design;

FIG. 2 is a left side elevational view thereof;

FIG. 3 is a right side elevational view thereof;

FIG. 4 is a rear elevational view thereof;

FIG. 5 is a top plan view thereof; and,

FIG. 6 is a bottom plan view thereof.

The broken lines around the perimeter of the glove represent top stitching.

A feature of the ornamental design is that the glove caddy may be either left handed as shown or right handed.
